EUGENE R. KISSINGER AND ROY H. KISSINGER, OF COLUMBUS, OHIO.

ADJUSTABLE STRIKER PLATE FOR DOORS.

Application filed March 23, 1927. Serial No. 177,706.

This invention relates to improvements in latch plates for use in connection with adjustable striker plate for doors and more particularly the swinging doors of automobile bodies, and the primary object of the invention resides in the provision of an adjustable plate through the medium of which compensation may be made for wear on the locking surface of both the plate and the door, in order that such doors may be maintained in a tight properly locked condition and to avoid the presence of rattles and looseness which inevitably occurs in ordinary constructions of this kind after the doors have been in use for some time.

For a further understanding of the invention reference is to be had to the following description and the accompanying drawing, wherein:

20 Figure 1 is a horizontal sectional view taken through the cooperating parts of an automobile door and door jamb, showing more particularly the construction of the improved adjustable striker plate comprising the present invention,

Figure 2 is a perspective view of the door jamb showing the plate in its operative position therein.

Figure 3 is a perspective view of the base portion of the plate, and

Figure 4 is a perspective view of the separable portion thereof.

Referring more particularly to the drawing the numeral 1 designates a door frame or jamb of the type commonly found in automobile body constructions, and the numeral 2 designates the usual form of swinging door, and although the hinge mounting for the door has not been shown, it will be understood that the latter is of standard construction and operation. The door as usual is provided with a latch mechanism consisting of the usual spring pressed bolt 3, the beveled nose portion 4 of which being adapted to extend beyond the confines of the door and yet to be resiliently retractible from such extended position.

The improved striker plate, comprising the present invention consists of two sections, a main or base section 5 and a removable or adjustable separable section 6. The base section 5 is formed from a single casting or the like and is of substantially wedge shaped form, having the thinner edge 7 thereof located toward the front of the door jamb and the thicker or inner edge portion 8 so arranged

as to present a locking face 9, which is adapted to be engaged by the back of the bolt 3, as shown in Figure 1, so as to hold the door in locked relationship with respect to the jamb.

The forward portion of the base section 5 has the beveled surface thereof provided with teeth or vertical serrations 10, which are adapted to engage with similar teeth or serrations 11 provided on the removable section 6, the teeth 10 and 11 providing for close locking engagement between the sections 5 and 6. The removable section is formed with an opening 12, which is adapted to register with a longitudinally extending slot 13 formed in the main section and extending from the front edge 7 thereof longitudinally toward the rear or inner edge portion of said main section. A screw or the like 14 has its headed end seated within the countersunk opening 12, while the shank of the screw passes through the forward portion of the slot 13 and is threaded into the wooden post constituting a part of the door frame 1. Also, a second screw 15 has its headed end received within the countersunk portion of the slot 13, and the shank of the screw 15 is likewise threaded into the door frame 1. The removable section 6 is of wedge shaped form so that its inner edge will produce a locking surface 16, adapted to provide a safety locking shoulder so that if the bolt 3 is accidentally disengaged with the surface 9, the swinging of the door in an outward direction would be arrested by the engagement of the bolt 3 with the surface 16.

It has been found that after a certain period of use considerable wear takes place between the normally engaging surface of the bolt 3 and the main section 5. This wear results in rattle and looseness on the part of the door and is a source of considerable annoyance in vehicle operation. Ordinarily to overcome the same it has been necessary in the past to substitute new striker plates involving considerable expense and labor. However, by the present invention this may be avoided by simply loosening the screws 14 and 15, and moving the base plate of the striker toward the bolt 3, as indicated by the arrow in Figure 1, in order that proper registration may be effected between the bolt and the face 9 to overcome the developed looseness and rattle. This result could not be permanently achieved by merely providing the base section 6 with a slot, since the adjustment could not be maintained for any length of time, but

by providing the separable locking section 6 which it will be observed is not provided with a slot, but with an opening, the permanency of the adjustment can be maintained indefinitely or until additional wear sets in.

The construction has the advantage of being readily and cheaply manufactured and provides a distinct improvement and refinement in automobile door lock construction.

10. What is claimed is:

1. As a new article of manufacture, a metallic striker for door locks comprising a main section of wedge like form provided with a longitudinally extending slot, and a separable locking section mounted upon the outer portion of said main section and formed with an opening in registration with said slot, said opening and slot being adapted to receive fastening elements for retaining the striker 20 in an applied position.

2. A lock striker comprising a main body section of wedge like form having a longitudinally extending slot provided therein, the thicker or inner edge portion of said section being formed to produce a locking face for engagement with a latch bolt, a removable locking section applied to the outer edge portion of said main section and formed to include an opening disposed in registration with 30 said slot, said removable locking section being

of wedge like form and having its inner edge portion formed to present a locking shoulder adapted for engagement with a latch bolt, and a fastening device arranged to pass through the opening and slot in said sections to retain the latter in operative positions of adjustment.

3. A striker for automobile locks comprising a wedge shaped main section provided with a longitudinally extending open ended slot, a forward portion of said section being provided with a toothed surface, a locking section of wedge form having a toothed surface arranged to interlock with the corresponding surface of said main section, said locking section is formed with an opening in registration with the slot in the main section, the slot and said opening being countersunk to receive the headed ends of screws passing therethrough, the outer surfaces of 50 said screws lying in the same plane with that of the outer surfaces of said sections, one of said screws serves to maintain the two sections in operative positions of adjustment and to retain the striker in an applied position with 55 in a door jamb.

In testimony whereof we affix our signatures.

EUGENE R. KISSINGER.
ROY H. KISSINGER.
